UNITED STATES PATENT OFFICE

JAMES FRANCIS DUNN, OF SALT LAKE CITY, UTAH.

PEDESTAL BRACE-BOLT.

SPECIFICATION forming part of Letters Patent No. 634,748, dated October 10, 1899.

Application filed February 27, 1899. Serial No. 707,006. (No model.)

To all whom it may concern:

Be it known that I, JAMES FRANCIS DUNN, of Salt Lake City, in the county of Salt Lake and State of Utah, have invented a new and 5 Improved Pedestal Brace-Bolt, of which the following is a full, clear, and exact description.

This invention relates to a pedestal brace-bolt for locomotives; and the object is to provide an effective means for bracing the pedestal, which means may be readily removed in a downward direction without interfering with the spring-rigging of the locomotive.

This specification is the disclosure of one 15 form of the invention, while the claims define the actual scope thereof.

Reference is to be had to the accompanying drawings, forming a part of this specification, in which similar characters of reference indicate corresponding parts in all the views.

Figure 1 is a side elevation of the invention with parts in section. Fig. 2 is a detail plan view of the bracing-sleeve. Fig. 3 is a sectional view on the line 3 3 of Fig. 1. Fig. 25 4 is a similar view on the line 4 4 of Fig. 1, and Fig. 5 is a sectional view of a slight modification.

The pedestal-jaws 6 are provided at their lower ends with downwardly-extending slots 30 7, terminating at their outer ends in round concavities 8. The upper side walls of the slots 7 are rounded to snugly receive the binding-bolt 9, the head 10 of which is provided with a boss 11, fitted in the concavity 8 of the adjacent slot 7, and the nut 12 of which is provided with a similar boss 14, fitting in the other concavity 8. By these means the jaws 6 are braced against movement apart from each other, and at the same time the bolt is 40 prevented from dropping out by the circular bosses 11 and 14, bearing in the similarly-shaped concavities 8. When, however, the nut 12 is removed, the bolt 9 may be moved lengthwise and the boss 11 of the head of 45 the bolt readily dislocated from the coacting recesses 8, thus permitting the movement of the bolt downward through the slot 7 and avoiding the necessity of displacing the spring-rigging, which, as is well known, is 50 located at each side of the pedestal, and which when in place would prevent the removal of the bolt longitudinally.

The sleeve 15 surrounds the bolt between the pedestal-jaws and has enlarged end portions 16 with flanges 17 at each outer side 55 edge thereof. These flanges are adapted to take over the respective sides of the pedestal-jaws at the lower portions thereof, thus securely bracing the jaws against movement toward each other. When the parts are to 60 be assembled, the sleeve 15 is first placed on the bolt and the bolt and sleeve moved upward together, after which the nut 12 is tightened to force the bosses 14 and 11 into the respective recesses 8, and thus lock the several parts in place.

The modification shown in Fig. 5 consists in substituting a washer 11^a for the bosses 11 and 14 shown in Figs. 1 to 4. This washer surrounds the bolt and bears against the 70 head and fits in the concavity to operate the same as the bosses before described.

Having thus described my invention, I claim as new and desire to secure by Letters Patent—

1. In a pedestal-brace, the combination of a sleeve, a bolt extending through the sleeve, and means at each end of the bolt for fastening the bolt in place, such means also serving to enter recesses in the pedestal-jaws, to 80 prevent the dropping of the bolt.

2. In a pedestal-brace, the combination of a bolt, and means at each end of the bolt for drawing the bolt into operative position, such means also serving to enter recesses in the 85 pedestal-jaws, to prevent the dropping of the bolt.

3. The combination of pedestal-jaws having slots formed in their lower ends, such slots opening downward, and terminating at 90 their outer ends in recesses, a bolt extending through the slots, and means at each end of the bolt for drawing the bolt into operative position, such means also serving to enter the recesses in the pedestal-jaws, to prevent the 95 dropping of the bolt through the slots.

4. The combination of pedestal-jaws having slots therein opening at their outer sides and terminating at their outer ends in recesses, a bolt fitted in said slots, means at 100 each end of the bolt for drawing the bolt into operative position, such means serving also to enter the recesses in the pedestal-jaws to hold the bolt in place, and a sleeve surround-

ing the bolt and fitting between the pedestal-jaws.

5. The combination with a pedestal having slots in the jaws thereof, such slots opening at the lower ends of the pedestal-jaws, of a bolt fitted in the slots and means at the ends of the bolt for drawing the bolt into opera-

tive position and also for preventing the dropping of the bolt downward through the slots.

JAMES FRANCIS DUNN.
